UNITED STATES PATENT OFFICE

2,644,570

MATERIAL ELEVATOR

Stanley D. Russell, Racine, Wis., assignor to J. I. Case Company, Racine, Wis., a company of Wisconsin

Application July 11, 1946, Serial No. 682,892

11 Claims. (Cl. 198—122)

1

My invention relates to material elevators.

One of the objects of my invention is to provide a portable endless elevator capable of use under different conditions requiring different heights of elevation of the conveyor chute in which the endless conveyor support is mounted to swing for adjustment to different heights about an axis coaxial with or adjacent the axis of a pair of ground-engaging wheels on which the conveyor is moved from place to place.

A further object of the invention is to provide such a construction in which the endless conveyor is driven from one of the ground-engaging wheels which is supported off the ground for this purpose.

A further object is to provide a construction as set forth in the above objects in which the elevator is motor driven and the motor support is mounted for movement from transport position to operating position.

A further object is to provide improvements in the elevator chute, chute-supporting means and endless conveyor.

A further object is to provide an endless conveyor construction having improved chute means by which the conveyor may be adapted for handling different classes of material, for example, bales of hay, with one adaptation of the conveyor, and shelled grain with a different adaptation.

Further objects and advantages of the invention will be apparent from the description and claims.

In the drawings, in which two embodiments of my invention are shown,

Figure 1 is a side elevational view of an endless chain elevator;

Fig. 2 is a plan view of the elevator in lowered position;

Fig. 3 is a section substantially on the line 3—3 of Fig. 2;

Fig. 4 is a section substantially on the line 4—4 of Fig. 3;

Figs. 5, 6, 7 and 8 are sections substantially on the lines 5—5, 6—6, 7—7 and 8—8 of Fig. 4;

Fig. 9 is a perspective view of the motor base mounting;

Fig. 10 is a section on the line 10—10 of Fig. 2;

Fig. 11 is a view from the left of Fig. 2;

Fig. 12 is a section on the line 12—12 of Fig. 3;

Fig. 13 is a side elevational view from the right of Fig. 3 showing part of the wheel;

Fig. 14 is a section on the line 14—14 of Fig. 1;

Fig. 15 is a bottom view of the elevator support shown in Fig. 1;

2

Fig. 16 is a perspective view of the upper end of the elevator showing a drawbar attachment;

Fig. 17 is a perspective view of the upper end of the elevator showing a suspension support;

Fig. 18 is a perspective view of the lower end of the elevator showing an auxiliary chute attachment;

Fig. 19 is a vertical axial sectional view similar to Fig. 3 but showing a different form of drive; and

Fig. 20 is an elevational view from the left of Fig. 19.

Referring to the drawings in detail, and first to Figs. 1—18, incl., the portable elevator shown comprises a pair of coaxial ground-engaging wheels 1 and 2 on which the elevator is transported from place to place, an elongated chute and conveyor support 3 swingably mounted for height adjustment about the axis of said wheels 1 and 2, an endless chain conveyor 4 mounted on said support, and a pair of sprockets 5 and 6 mounted at opposite ends of said swingable support over which the chain runs for supporting it in extended position.

25 In this form means are provided for driving the conveyor chain from one of the ground-engaging wheels 1. For this purpose means are provided for supporting the wheel 1 above the ground. This wheel 1, when elevated, is used to drive the lower sprocket 5. A motor 7 is provided for driving this elevated wheel 1, the support 8 for which is mounted to swing from an elevated position for transport to a lowered position resting on the ground when the conveyor is to be used.

To enable the elevated wheel 1 to be used for driving the sprocket, the axle section or shaft 9 on which the elevated wheel is secured is rotatable in spaced bearings 10 secured to the swingable elevator support 3. The other wheel 2 is rotatably mounted on an axle section 11 secured to the conveyor support. The use of the axle section 9 as a drive shaft reduces the weight and cost. Since the drive axle section does not have to revolve in the stationary wheel 2 when the elevator is in operation, less power is required since no part of the elevator weight is carried by that section 9 of the axle which drives the elevator. This construction also lessens the bearing wear 45 since it does not turn in the ground-engaging wheel 2 during elevator operation. If it is desired to maintain the drive axle in horizontal position, the nondriving wheel may be mounted in a suitable chuck 12 which will raise it above the ground to about the same height as the drive

wheel. This chuck will also hold the conveyor in position as shown in Figs. 3 and 13. By providing a larger wheel (not shown) on the side of the conveyor opposite the drive wheel 1, the necessity for raising the nondrive wheel 2 by means of a chuck may be avoided since, when the drive wheel is elevated, the axle may then be in horizontal position. It is apparent that the axle could be made in one piece rotatable with the drive wheel 1 and rotatable in the hub of the chuck-engaging wheel 2. Using the elevated ground wheel 1 as a belt drive eliminates the cost of a conventional gear reduction and avoids the necessity of an additional pulley. It simplifies the lubrication of the elevator and increases its efficiency by eliminating the gear reduction. It also lessens the weight.

For supporting the drive wheel 1 in elevated position, the swinging support 8 is provided, pivotally mounted on a bearing sleeve 13 secured to the conveyor chute to swing from the dotted-line transport position to the full-line wheel-supporting position shown in Fig. 4. This swinging support is provided with a foot portion 14 of channel cross section as shown in Fig. 5, to 25 which the tubular leg portion 15 may be secured as by spot-welding or the like. For securing the leg 15 in raised transport position, a threaded stud 16 is secured thereto which may extend through a hole in an angle iron 17 secured to the chute 3 when the leg is in raised position and onto the end of which may be screwed a hand nut 18 for holding the leg in raised position.

In order to insure that the motor is mounted in proper relation with respect to the drive wheel, a channel-like arm 19 is provided, one end of which fits within the channel-like foot 14 and is secured thereto by means of a threaded stud 20 welded to the foot and extending through a hole in the arm 19 as shown in Fig. 5. For securing this arm to the foot, the same nut 18, which was used in securing the leg 15 in elevated position, may be used by screwing it onto the upper end of the stud 20.

For securing the motor 7 to the arm 19, a supporting plate 21 is provided having holes therein through which headed and threaded bolts 22 extend, which bolts also extend through slots 23 in the upper web of the channel-like arm 19 as shown in Figs. 7, 8 and 9. Securing hand nuts 24 are provided threaded onto the upper ends of these bolts. By longitudinal adjustment of this motor support 21, the proper tension in the drive belt 25 may be secured. This mounting of the motor enables the elevator chute to be raised or lowered to any angle without changing the drive belt adjustment since the leg 15 to which the motor-supporting arm 19 is secured is pivoted to swing about the same axis as that about which elevator chute 3 swings in its raising and lowering movement.

In order to further support the motor base and the supporting arm, a plate 26 is welded to the lower edges of the flanges of the arm 19 and a post 27 is welded to this plate on the upper end of which the lower face of the motor support 21 may rest, as shown in Figs. 4, 7, 8 and 9. The motor base 28 may be secured to the supporting plate 21 by means of bolts 29 as shown in Figs. 4, 7 and 8. In order to anchor the elevator and motor securely, the arm may be provided with an opening through which a peg may be driven into the ground, which might be use-

ful, for example, when the elevator is operated on a side hill or extremely uneven ground.

The conveyor chute 3 comprises a metal bottom sheet 30 (Figs. 14 and 18), extending longitudinally of the chute having down-turned side flanges 31, and side plates 32 forming, with the bottom of the chute, a longitudinal channel in which the elevated material travels. The lower edges of the side plates are secured to the down-turned flanges in any suitable manner, as by spot-welding. The bottom sheet is reinforced by a plurality of longitudinally-spaced angle irons 33 extending transversely of the bottom support and spot-welded thereto, the ends of the angle irons being spot-welded to the down-turned flanges 31, providing a light, strong construction.

In order to provide a support for material, such as bales of hay, as they travel along the chute and to keep this material from bearing too hard on the conveyor chain, a pair of wooden coplanar wing-like material-guiding and supporting runners 34 are secured to the bottom plate on the upper side thereof on opposite sides of the endless conveyor. Any suitable securing means may be provided, such as bolts 35, extending through the runners and the bottom of the chute.

Transversely-extending blades or paddles 36 are secured at intervals to the conveyor chain for engaging the material being elevated and pushing it along the chute. For material such as baled hay, or the like, these pusher blades may be provided with flanges 37 extending forwardly from the upper edge of the blade and these flanges may be serrated as shown in Fig. 2 in order to bite into the material being elevated. This forwardly-extending flange causes the blade to engage the bale properly even though it may be tilted back somewhat in carrying the bale up to the chute. The serrated edge grips the bale even though it is dropped on top of the serrated flange. It is intended that the bales be dropped ahead of the blades, but sometimes a bale happens to fall directly on top of the blades. A blade having a smooth leaning edge would slip out from under, whereas the saw-tooth edge grips the bale.

In order to secure the right amount of sag in the lower run of the chain, the upper sprocket 50 6 is made longitudinally adjustable. For this purpose, it is rotatably mounted in a yoke 38, the stem 39 of which is slidably but nonrotatably mounted in a sleeve 40 secured to the transversely-extending angle irons extending across and secured to the bottom of the chute. For adjusting the stem 40^a of the yoke, it is threaded as shown in Figs. 2 and 10, and an adjusting nut 41 is screwed onto this threaded stem and bears against the angle iron 33 so that by turning this nut the stem may be adjusted longitudinally. In order to keep the stem 40^a from turning in the sleeve, a screw 42 is provided extending through a slot in the bottom of the sleeve 40 and threaded into the stem.

65 A combined guard and handle member 43 is provided at the upper end of the chute comprising a U-shaped bar secured to the upper end of the chute and embracing the sprocket wheel 5 and yoke 38. This hand rail 43 also serves as a guard to prevent bales being discharged from rolling back underneath the elevator and engaging the pusher plates 36 and damaging them.

After the elevator is lowered to the ground, the operator, by the use of the hand rail 43, may

raise that end of the elevator and push it to a new location.

Various means may be provided for supporting the upper end of the conveyor in elevated position. For raising it to elevated position a rope or cable 44 may be secured to the bail or handle 43 and to the sheave of a pulley 44^a forming part of a block and tackle arrangement, the block of which may be secured to any convenient support.

In order to support the chute 3 in vertically adjusted position, for example in proper relation with respect to a hayloft floor, a stand is provided comprising a pair of legs 45 (Figs. 14 and 15, one pivotally secured on each side of the chute, and a pair of braces 46, one on each side of the chute, each having one end secured to one of the legs at 47 and its other end 48 pivotally secured to the side of the chute. This brace may be a two-piece longitudinally-extensible construction, each piece having a number of longitudinally-spaced openings 49 therein in which the securing bolts 50 may be placed. These legs and braces may be secured in various positions along the chute by providing the sides of the chute with suitably spaced holes 51 to receive the pivot bolts 48 and 52.

In cases where it is not convenient to support the chute from beneath, an overhead suspension yoke 53 may be provided, the lower ends of which are pivotally secured to a pivot rod 54 secured to brackets 55 on the sides of the chute as shown in Figs. 1 and 17. This suspension yoke may be used, for example, in an open building, the upper end of the yoke being supported by a cable, or the like, from the upper bracing or roof structure of the building. This suspension yoke is large enough for the bales to pass therethrough even though the bales are hanging over the sides of the chute and even though the chute is raised to the highest practical operating position of forty-five degrees. This yoke may be raised and lowered by a block and tackle arrangement similar to that described in connection with the rail. This block and tackle provides flexibility and is therefore convenient in that it may be fastened at its upper end at most any height within a building and the elevator may be held in any position or angle during its operation by the use of the yoke. For instance, if a block of bales is being piled in a barn and the elevator is being used to elevate the bales to the top of the pile, by the use of the block and tackle and the suspension yoke the elevator may be raised after each tier of bales is laid, thereby eliminating all lifting.

In order to prevent the chain from swaying up, down and sidewise while the elevator is in operation, a sheet metal guide 56 is provided (Figs. 1 and 14), secured to the angle irons 33 on the bottom plate of the chute beneath which guide the conveyor chain 4 travels. This is not intended as a chain tightener. The chain is tightened by means of the adjustment of the sprocket previously described so that it bears only slightly against the guide.

To facilitate delivering the material to the lower end of the chute, a hopper-like construction (Figs. 1, 2 and 18) is provided comprising a pair of sloping side plates 57, on each side of the chute, having their lower edges bolted to the side plates 32 of the chute. Under certain conditions, for example when bales are to be delivered to the elevator from wagons or trucks, an end member 58 (Figs. 2 and 11) is provided extending between the sloping side members 57. 75

This hopper end may be removed under certain conditions, for example when delivering hay to the elevator from sleds or the like at the ground level.

5 In order to prevent bales which might accidentally slide down the chute from sliding out from the bottom end of the chute and perhaps injuring someone, a safety rod 59 is provided which extends between and is secured to the sides of the chute as shown in Figs. 2, 3, 12 and 19.

10 In order to adapt the elevator for material such as small grains and ear corn, an auxiliary chute may be provided, the sides of which lie closer to the conveyor blades than do the sides of the bale elevator chute. This construction is shown in Fig. 18. This auxiliary chute comprises a pair of lower downwardly and inwardly inclined wings or guide plates 60 extending the length of the chute, one on each side of the conveyor blades 20 36 and detachably secured to the bale-supporting runners 34.

25 In order to provide a hopper for the smaller chute, a pair of sloping hopper members 61 is provided, one for each side of the chute, the lower edges of which are secured to the upper edges of the plates 60 and the upper edges of which are secured to the upper edges of the large hopper plates 57.

30 For elevating hay or the like only a few widely spaced pusher blades 36 need be used, sometimes only two. For small grain and ear corn a greater number of blades are used, perhaps one every twelve inches. The same type of blade may be used both for bales of hay and small grain.

35 Suitable guard means may be provided for the lower end of the conveyor as it travels around the lower sprocket comprising an upper curved guard plate 62 (Fig. 12) and a lower curved guard plate 63. The upper edge of the upper plate may be secured to the transversely-extending safety rod 59 and the lower edge may rest on a transverse supporting bar 64. The lower edge of the lower guard 63 may be secured to a transversely-extending rod 65 and its upper edge may be supported by the transverse bar 64.

40 For transporting the elevator for any distance, a detachable hitch may be provided (Figs. 16 and 17). This comprises a channel-like drawbar 66 having a hitch yoke 67 secured to its front end. For attaching it to the end of the chute, an L-shaped pin 68 is secured to the rear end of the drawbar, the longitudinally-extending portion of which is insertable into an opening in one of the angle irons 33 secured to the bottom of the chute. An intermediate portion of the drawbar is secured to the upper angle iron 33 by means of a pair of bolts 69 extending through openings in this angle iron and in registering openings in the webs of the short angle irons 70 secured to the sides of the drawbar.

45 In transporting the elevator, the hitch may be secured to a tractor, car, baler, or the like.

The construction shown in Figs. 19 and 20 may be the same as that previously described except as to the drive between the motor 7 and the lower sprocket 4. In this form it is not necessary to raise either of the ground-engaging wheels 2 or 71. The construction shown comprises a bearing sleeve extension 72 from the bearing housing 73 in which the axle section is rotatably mounted and on which sleeve extension 72 the ground-engaging wheel 71 is rotatably mounted, a drive pulley 73^a keyed to the axle section 9, a motor support 74 for the motor 9 swingably mounted on the bearing housing and movable from a trans-

port position to a position of use; and a belt 25 from the motor pulley to the drive pulley 13. Any suitable means (not shown) may be provided for holding the swinging motor support 14 in transport position. In this form the elevator is transported to position for use, the motor support 14 on which the motor 1 may be mounted is swung down until its swinging end rests on the ground, and the elevator is then ready for use.

Further modifications will be apparent to those skilled in the art and it is desired, therefore, that the invention be limited only by the scope of the appended claims.

Having thus described my invention, what I claim and desire to secure by Letters Patent is:

1. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, and means for supporting one of said wheels above the ground, one of said rotors being rotatable with the elevated wheel.

2. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, means for supporting one of said wheels above the ground, one of said rotors being rotatable with the elevated wheel, and a motor for driving said elevated wheel.

3. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, means for supporting one of said wheels above the ground, and a rotatable axle to which the elevated wheel and one of said rotors are secured.

4. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, means for supporting one of said wheels above the ground, and a rotatable axle to which the elevated wheel and one of said rotors are secured, the unelevated wheel being mounted on a nonrotatable axle.

5. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, and means for supporting one of said wheels above the

ground, one of said rotors being rotatable with the elevated wheel, said wheel-supporting means comprising a support mounted to swing about the axis of said wheel from a wheel-supporting position to a nonsupporting position.

6. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, means for supporting one of said wheels above the ground, one of said rotors being rotatable with the elevated wheel, said wheel-supporting means comprising a support mounted to swing about the axis of said wheel from a wheel-supporting position to a nonsupporting position, and a motor for driving said elevated wheel having means for securing it in driving position on said support.

7. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, means for supporting one of said wheels above the ground, one of said rotors being rotatable with the elevated wheel, said wheel-supporting means comprising a support mounted to swing about the axis of said wheel from a wheel-supporting position to a nonsupporting position, a motor for driving said elevated wheel having means for securing it in driving position on said support, and a drive belt from said motor to said elevated wheel.

8. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, means for supporting one of said wheels above the ground, one of said rotors being rotatable with the elevated wheel, said wheel-supporting means comprising a support mounted to swing about the axis of said wheel from a wheel-supporting position to a nonsupporting position, and a motor for driving said elevated wheel having means for securing it in driving position on said support comprising a strut on which the motor is mounted, detachably secured to said support to lie in horizontal position when the wheel is elevated.

9. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, one of said rotors being coaxial with said wheels, means for supporting one of said wheels above the ground, one of said rotors being rotatable with the elevated wheel, said wheel-supporting means comprising a support mounted to swing about the axis of said wheel from a wheel-supporting position to a nonsupporting position, a motor for

driving said elevated wheel having means for securing it in driving position on said support comprising a strut on which the motor is mounted, detachably secured to said support to lie in horizontal position when the wheel is elevated, said strut having a threaded stud secured thereto for passing through a hole in said support, said support having a stud secured thereto, an anchor member having an opening through which said stud may extend when the support is swung to inoperative position, and a hand nut for said studs for holding them in anchored position.

10. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, and means for supporting one of said wheels above the ground, one of said rotors being driven from the elevated wheel.

11. A portable elevator comprising a pair of coaxial ground-engaging wheels, an elongated endless conveyor support swingably mounted for height adjustment movement about the axis of said wheels, an endless conveyor mounted on said support, a pair of rotors spaced longitudinally of said swingable support for supporting the endless conveyor in extended position, means for supporting one of said wheels above the ground, one

of said rotors being driven from the elevated wheel, and a motor for driving said elevated wheel.
